UNITED STATES PATENT OFFICE

159,623

HEADLIGHT LENS FOR AUTOMOBILES

Eva C. James, Charleston, W. Va.

Application April 15, 1949, Serial No. 2,028

Term of patent 14 years

(Cl. D48—32)

To all whom it may concern:

Be it known that I, Eva C. James, a citizen of the United States of America, residing at Charleston, in the county of Kanawha and the State of West Virginia, have invented a new, original, and ornamental Design for a Headlight Lens for Automobiles, of which the following is a specification, reference being had to the accompanying drawing, forming part hereof.

In the drawing:

Figure 1 is a front elevation of a headlight lens for automobiles, showing my new design.

Figure 2 is a side elevation thereof.

Figure 3 is a rear elevation of the headlight lens.

Figure 4 is a vertical section on the line 4—4 of Figure 1.

Figure 5 is a fragmentary cross section on the line 5—5 of Figure 1.

I claim:

The ornamental design for a headlight lens for automobiles, as shown.

EVA C. JAMES.
